UNITED STATES PATENT OFFICE

96,703

DESIGN FOR A CHAIR SEAT FRAME

Arthur R. Schwarzkopf, Chicago, Ill., assignor to
Theo. A. Kochs Company, Chicago, Ill., a cor-
poration of Illinois

Application December 17, 1934, Serial No. 54,447

Term of patent 7 years

To all whom it may concern:

Be it known that I, Arthur R. Schwarzkopf, a citizen of the United States, residing at Chicago, in the county of Cook and State of Illinois, have invented a new, original, and ornamental Design for Chair Seat Frames, of which the following is a specification, reference being had to the accompanying drawing, forming part thereof, wherein—

Figure 1 is a perspective view of the seat frame

on a reduced scale, looking from the side and rear; and

Figs. 2 and 3 are side and rear elevational views, respectively, of the seat frame, showing my new design.

I claim:

The ornamental design for a chair seat frame, as shown and described.

ARTHUR R. SCHWARZKOPF.
